UNITED STATES PATENT OFFICE.

ROUSSEAU FORBY HAYNES, OF LOWELL, MASSACHUSETTS.

MAGAZINE-HOLDER.

972,531.

Specification of Letters Patent. Patented Oct. 11, 1910.

Application filed February 16, 1910. Serial No. 544,202.

To all whom it may concern:

Be it known that I, ROUSSEAU F. HAYNES, a citizen of the United States, and a resident of Lowell, in the county of Middlesex 5 and State of Massachusetts, have invented a new and Improved Magazine-Holder, of which the following is a full, clear, and exact description.

The invention is a magazine holder by 10 which the modern heavy magazine may be conveniently grasped and supported while reading, and belongs to that class of such devices as embody a tubular hand-grip of spring metal split lengthwise and having 15 opposed longitudinal jaws at the edges, arranged to firmly bind on the opposite sides of the magazine adjacent to the rear edge.

The object of the invention is to provide in connection with the hand-grip, stops 20 which are arranged to prevent the application of the jaws to the magazine to an extent to interfere with the opening of the magazine.

Reference is to be had to the accompanying drawings forming a part of this specification, in which similar characters of reference indicate corresponding parts in all the views.

Figure 1 is a perspective view of a holder 30 constructed in accordance with my invention as applied to a magazine; Fig. 2 is an inner face view of the holder; Fig. 3 is a plan of the same; Fig. 4 is a side view of a modified form of the holder; Fig. 5 is a plan 35 of the holder shown in Fig. 4; and Fig. 6 is a plan of a still further form of the holder.

Referring more particularly to the form 40 of the invention as illustrated in Figs. 1, 2 and 3, the holder comprises a tubular hand-grip 10 of spring sheet metal, the tube being split lengthwise, with the edge portions turned to provide opposed jaws 11, arranged to engage the magazine at opposite sides adjacent to the rear edge, as shown in Fig. 1.

45 The jaws at each end of the holder are separated from the body of the tubular hand-grip by slotting the tube at these points and turning the metal inwardly at the inner edges of the slots to form opposed 50 lips 12, the lips serving to limit the insertion of the magazine between the jaws and pre-

vent the magazine from passing within the body of the tube, in which event the opening of the magazine would be interfered with. The jaws 11 at one end are extended slightly 55 beyond the end of the hand-grip and flare outwardly to facilitate the application of the holder to the magazine, as by passing the holder over the rear edge of the magazine from one end. 60

In the form of the invention shown in Figs. 1 to 3, inclusive, the holders are corrugated circumferentially, with the corrugations extending through the jaws. This construction adds stiffness and strength to the 65 holder and adapts it to be grasped with greater firmness.

In the form of the invention shown in Figs. 4 and 5, the holder is in all respects the same as that described, except that it is 70 provided with a helical spring 13 arranged interiorly of the grip, with its ends connected thereto adjacent to the jaws and tending to draw the latter together, thus assisting the spring of the metal to forcibly press the 75 jaws to the magazine.

In the form of the invention shown in Fig. 6, the edges of the metal at the split portion of the grip instead of being turned outwardly to form the opposed jaws, are 80 turned inwardly, forming the opposed jaws 11^a, contained within the body of the tube, the jaws 11^a having inwardly-turned lips 12^a, corresponding to the lips 12, and serving a like purpose. 85

Any form of the holder shown, when applied to the magazine, affords a substantial handle or grip by which the magazine is grasped, and does not interfere with the turning over of the pages. 90

Having thus described my invention, I claim as new and desire to secure by Letters Patent:

1. A magazine holder comprising a tubular hand-grip of spring material split along 95 its length and provided with opposed longitudinal jaws at the edges, arranged to bind the magazine at opposite sides adjacent to the rear edge, and inwardly-extended lips at the inner edges of the jaws to limit the insertion of the magazine. 100

2. A magazine holder comprising a hand-

grip having opposed spring clamping jaws adapted to bind a magazine at opposite sides adjacent to the rear edge, and stops arranged to prevent the application of the grip to the 5 magazine to an extent to interfere with the opening of the magazine.

In testimony whereof I have signed my

name to this specification in the presence of two subscribing witnesses.

ROUSSEAU FORBY HAYNES.
